UNITED STATES PATENT OFFICE

ERNEST B. MILLER AND AXEL BENZON, OF BALTIMORE, MARYLAND, ASSIGNEES TO THE SILICA GEL CORPORATION, OF BALTIMORE, MARYLAND, A CORPORATION OF MARYLAND

REFRIGERATION

Application filed July 22, 1924, Serial No. 727,447. Renewed December 29, 1927.

This invention relates to refrigeration and more particularly to a species of the invention disclosed in application 675,929. This prior application discloses a method of refrigeration consisting in adsorbing in a porous material, vapor from a liquid, the adsorption taking place substantially in the absence of permanent gases, the evaporation of the liquid causing the refrigerating effect. The porous material adsorbs the vapor in its pores and thereafter the material is treated to liberate the adsorbed vapor, so that the material may be used for another adsorbing cycle.

One of the principal features of the present invention resides in the fact that the adsorbent is circulated, being used over and over and likewise the vapor from the refrigerating liquid is circulated so that it also is used over and over.

An apparatus for carrying out the method of the present invention comprises an evaporator, an adsorber, and an activator, said adsorber being in communication with the evaporator, both said parts being substantially free from permanent gases. Means is provided to feed the adsorbing material into the vapor in the adsorber, whereby said vapor is adsorbed causing evaporation of the liquid and thus giving a refrigerating effect. The adsorbing material is then discharged into the activator where the vapor is driven off and thereafter the adsorbing material is again fed into the adsorber. The vapor driven off from the material in the activator is condensed and returned to the liquid in the evaporator.

In order to maintain the evaporator and adsorber free from permanent gases, a small vacuum pump has its inlet in communication therewith.

Other objects and features of novelty will be apparent from the description taken in connection with the drawings, in which: Figure 1 is a longitudinal vertical sectional view through an apparatus constructed in accordance with the present invention;

Figure 2 is an end elevation of the apparatus, certain parts being shown in section; and

Figures 3 and 4 are perspective views of a bucket wheel employed in the adsorber.

Referring to the drawings, which illustrate one form of the invention, a closed vessel 210, forming an evaporator chamber is in communication with an adsorber 213 by means of a conduit 212. The evaporator 210 contains a liquid, such as brine or water, which is evaporated to obtain the refrigerating effect. In order to free the adsorber and evaporator of permanent gases and maintain them substantially free of such gases, means, such as a motor driven vacuum pump 214, is provided, said pump having its inlet in communication with the adsorber by means of pipe 214a.

The adsorbing material, in finely divided condition, is fed into the adsorber 213, passes therethrough and is discharged into the activator 239, and then by means of conveyor 241 is returned to the adsorber. The activator 239 is in communication with a condenser 234 wherein the vapor liberated from the adsorbing material is condensed and returned to the evaporator by means of pipe 243.

It will be noted that the adsorbing material circulates in a closed cycle, first adsorbing vapor, then being treated to liberate the adsorbed vapor and thereafter being returned to the adsorber for use again. Likewise, the refrigerating liquid circulates in a closed cycle. It is adsorbed in the porous material, thereafter freed therefrom, then condensed in a condenser 234, and finally returned to the evaporator 210.

The adsorber of the apparatus consists of a cylindrical casing 244 having one end closed by a head 245 and the other by a partition, consisting of a plate 246 and heat insulating disk 246a. The adsorbing material supplied to the adsorber through the passage 238 formed in the nozzle 247 is agitated within the adsorber by any suitable means. As shown, a shaft 248 mounted in bearings 249 and 250 within the adsorber, carries a plurality of spiders 251, to the ends of the arms of which is secured a hollow rim 252 substantially rectangular in cross section. One end of shaft 248 projects through a trans-

verse screen 253, which is spaced from the head 245, thus forming a chamber within which is disposed a worm wheel 254 secured to said shaft 248. A motor frame forms a 5 casing 255, secured to the adsorber housing 244 and in communication with the interior of said adsorber, a heat insulating washer 255^b being interposed between the casing and housing. The motor shaft 255^a, projects into the 10 chamber 256 and carries a worm 257 gearing with the worm wheel 254. In this manner the shaft 248 is rotated by means of the motor and yet no stuffing boxes where leakage can occur, are employed, since the motor frame 15 is in direct communication with the adsorber housing. One side of each rim 252 carries the scoops 252^a, and the other side is formed with a ring shaped discharge opening 252^b. The interior of the rim may be divided by 20 partitions 252^c. The adsorbing material is scooped up by scoops 252^a when they are at their lowermost points of rotation, and then is discharged or spilled out through said discharge opening 252^b when the buckets are 25 traveling through the upper half of the rotation, so that the adsorbing material falls through the adsorbing chamber. As there 30 are a number of these devices along the length of the chamber, the adsorbing material is 35 very thoroughly agitated and distributed throughout the entire volume of said chamber, and advanced toward the left as viewed in Figure 1. Any other suitable means for this purpose may be employed. As shown 40 the spiders 251 are held in spaced relation by sleeves 252^c interposed between adjacent spiders. To cause the spiders to rotate with shaft 248, said shaft has flanges 252^d secured thereto and rods 252^e pass through said 45 flanges and spiders and clamp the whole assembly together.

The partition 246 is provided with a central opening aligned with the shaft 248, and a worm housing 258 extends through this 50 opening. On the adsorber side this housing has a hopper 259^a into which the last series of buckets 252 discharge the adsorbing material. The shaft 248 is extended through this worm housing 258 and carries a worm 55 259 by means of which the adsorbing material is conveyed horizontally to a discharge hopper 260.

It will be noted that the helix forming the 60 worm to the left of a point directly under the center of said discharge hopper 260 is reversed with respect to the helix at the right of said point. This novel construction is provided so that the adsorbing material will be 65 positively forced upwardly through the discharge hopper 260, a sufficient column of the adsorbing material being maintained within the discharge hopper, so that any difference of pressure between the interior of the worm housing and the activator chamber will not 70 destroy the seal effected by said column of ad-

sorbing material. In other words, this column of material acts to prevent a flow of vapors from one chamber to the other. From the hopper 260 the adsorbing material falls downwardly within the activator chamber. 70 The lower or bottom portion of the casing forming this chamber is heated in any suitable manner, as by means of a gas heater 261. The adsorbing material is caused to be moved toward the left as viewed in Figure 1 and 75 agitated by any suitable means, such as the paddles 262, carried by a rotatably mounted spider 263, supported in bearings 264 and 265. As shown, at its left end, this spider has a sprocket 266 driven by a chain 267 from a sprocket 268 on worm shaft 269. The adsorbing material falls through the passage 240 to the worm 241 within housing 270. This worm conveys the material to the supply 80 passage 238, and the material is cooled in its passage by water in jacket 270^a. At its right hand end, the worm has its helix reversed with respect to the helix on the main portion of the worm for the same purpose as described 85 in connection with forcing the material upwardly through the discharge hopper 260. The worm shaft 269 at its right hand end has a sprocket wheel 271 driven by a chain 272 from a sprocket 273 on shaft 248. Thus all 90 the moving parts of the apparatus, with the exception of the vacuum pump, are driven 95 from the motor 255.

The condenser 234 may be supplied with 100 cooling water through the inlet 274 and discharge the same through an outlet 275.

The pressure in the condenser is slightly greater than in the evaporator 210 and this difference in pressure causes the condensed liquid to be returned to the evaporator through conduit 243.

The pores of the adsorbing material required in the present method are ultra-microscopic, so that it is a very difficult matter to accurately determine and define their size. One satisfactory method of comparing the 110 size of the pores in two bodies and also the total volume of these pores consists in determining the amount of water that one gram of each body will adsorb when exposed to water vapor under definite conditions of temperature and partial pressure. The amount of water vapor adsorbed by a porous body at a given temperature and partial pressure depends both upon the size of the pores and upon the total interior volume of said pores. 115 Thus, two materials may have pores such that the internal volume of the pores in a gram of one material is the same as in a gram of the other, and yet the pores in one may be smaller than in the other. The one having the smaller pores will adsorb vapor at lower partial pressures than the other. In other words, very small pores are required in order to adsorb vapors at low partial pressure. To illustrate, 120 assume that a building brick has the same in-

ternal volume as an equal weight of silica gel. The brick, however, will adsorb substantially no water vapor at pressures below the normal vapor pressure of water, whereas the silica gel will adsorb large amounts at pressures very much lower than the normal vapor pressure of water. This is explained as follows: A liquid that wets a capillary tube will rise in the tube above the level of the surface of the liquid surrounding the same, the extent of the rise varying with the diameter of the tube. The vapor pressure of the liquid inside the tube is smaller than the vapor pressure at the level surface of the liquid outside the tube. This lowering of the vapor pressure by the liquid within the capillary tube is not appreciable until the diameter of the tube is extremely small, and the smaller the bore of the tube, the greater the decrease in vapor pressure. Consequently the vapor pressure within the pores of a body having small pores is less than in a body having large pores, with the result that the body having the smaller pores will adsorb vapors and gases at low partial pressures.

Thus, by determining the amount of a given vapor, water for example, which may be adsorbed by each of two porous bodies under the same condition of temperature and partial pressure, we have a means of comparing the size and volume of the pores in the two adsorbents. For example, a sufficient percentage of the total internal volume in silica gel is made up of such small pores that the gel will adsorb water vapor to such an extent that it will contain, at 30° C. about 21% of its weight of water when in equilibrium with water vapor at a partial pressure of substantially 22 mm. of mercury. Keiselguhr and boneblack under the above conditions will adsorb practically no water because the pores are too large. On the other hand highly activated charcoal, such as cocoanut charcoal activated in the presence of steam will adsorb more water than the silica gel mentioned above. It follows, therefore, that keiselguhr and boneblack have practically no pores as small as the greater part of the pores in silica gel. On the other hand, highly activated charcoal has more small pores than silica gel.

Materials suitable for the present invention should have pores of such size that the material will adsorb water vapor to such an extent as to contain not less than 10% of its own weight of water when in equilibrium with water vapor at 30° C. and a partial pressure of substantially 22 mm. of mercury.

Preferably silica gel is employed as the porous material. As stated this material has pores of such size that it will adsorb water vapor to such an extent as to contain substantially 21% of its own weight of water when in equilibrium with water vapor at 30° C. and a partial pressure of substantially 22 mm. of mercury. But other adsorbents

might be used provided they have a sufficient percentage of their internal volumes made up of small pores. Thus cocoanut charcoal activated in the presence of steam might be used with such liquids as can be easily liberated from the charcoal after being adsorbed therein. Other gels might be used, also, provided they are made with pores of the size required for this invention, i. e., gels of oxide of tin, aluminum, tungsten, titanium, iron, combinations of two or more of these oxides, or other metallic oxides, and gels consisting of silica oxide with one or more of the foregoing oxides.

The adsorbing action is a purely physical phenomenon, and involves no chemical action. Any body or material having pores of the size and quantity defined herein will act as stated and is suitable for use as an adsorbent in the present apparatus. At the present time, however, we have found silica gel to be the most satisfactory adsorbent for vapor from the liquid in the evaporator. In stating that the adsorbents for the present invention should adsorb not less than 10% of their weight of water vapor, we do not mean that is an exact line of demarcation between satisfactory and unsatisfactory adsorbents. The limit of 10% is intended to indicate in general about the maximum size pores that can be employed with some degree of success. Of course, for best results materials having smaller pores should be used.

Although one embodiment of the invention has been described in detail, it is to be understood that the invention is not thus limited, but includes modifications and changes which come within the scope of the appended claims.

Having thus described the invention what is claimed as new and desired to be secured by Letters Patent is:

1. A method of refrigeration, consisting in evaporating a liquid, adsorbing the vapor in a porous adsorbent material substantially in the absence of permanent gases, removing the material from the vapor, liberating the adsorbed vapor from the material and again bringing the material into contact with the vapor, the material having pores of such size that it will adsorb water vapor to such an extent as to contain not less than about 10% of its own weight of water when in equilibrium with water vapor at 30° C. and a partial pressure of substantially 22 mm. of mercury.

2. A method of refrigeration, consisting in evaporating a liquid, adsorbing the vapor in a porous adsorbent material substantially in the absence of permanent gases, removing the material from the vapor, liberating the adsorbed vapor from the material, cooling the material, and again bringing the material into contact with the vapor, the ma-

terial having pores of such size that it will adsorb water vapor to such an extent as to contain not less than about 10% of its own weight of water when in equilibrium with water vapor at 30° C. and a partial pressure of substantially 22 mm. of mercury.

3. A method of refrigeration, consisting in evaporating a liquid, adsorbing the vapor in a porous adsorbent material substantially 10 in the absence of permanent gases, removing the material from the vapor, liberating the adsorbed vapor from the material, condensing the vapor thus liberated and returning it to said liquid, and again bringing the material into contact with the vapor, the material having pores of such size that it will adsorb water vapor to such an extent as to contain not less than about 10% of its own weight 15 of water when in equilibrium with water vapor at 30° C. and a partial pressure of substantially 22 mm. of mercury.

4. A method of refrigeration, consisting in evaporating a liquid, adsorbing the vapor in a porous adsorbent material substantially 25 in the absence of permanent gases, removing the material from the vapor, liberating the adsorbed vapor from the material, condensing the vapor thus liberated and returning it to said liquid, cooling said material, and 30 again bringing the material into contact with the vapor, the material having pores of such size that it will adsorb water vapor to such an extent as to contain not less than about 10% of its own weight of water when in 35 equilibrium with water vapor at 30° C. and a partial pressure of substantially 22 mm. of mercury.

5. A method of refrigeration, consisting in evaporating a liquid, adsorbing the vapor 40 in a porous adsorbent material substantially in the absence of permanent gases, removing the material from the vapor, liberating the adsorbed vapor from the material and again bringing the material into contact with the 45 vapor, said material being a hard porous gel having pores of such size that it will adsorb water vapor to such an extent as to contain about 21% of its own weight of water when in equilibrium with water vapor at substantially 50 30° C. and a partial pressure of substantially 22 mm. of mercury.

6. A method of refrigeration, consisting in evaporating a liquid, adsorbing the vapor 55 in a porous adsorbent material substantially in the absence of permanent gases, removing the material from the vapor, liberating the adsorbed vapor from the material, cooling the material, and again bringing the material into contact with the vapor, said material being a hard porous gel having pores of such size that it will adsorb water vapor to such an extent as to contain about 21% of its own weight of water when in equilibrium 65 with water vapor at substantially 30° C. and

a partial pressure of substantially 22 mm. of mercury.

7. A method of refrigeration, consisting in evaporating a liquid, adsorbing the vapor in a porous adsorbent material substantially 70 in the absence of permanent gases, removing the material from the vapor, liberating the adsorbed vapor from the material, condensing the vapor thus liberated and returning it to said liquid, and again bringing the material into contact with the vapor, said material being a hard porous gel having pores of such size that it will adsorb water vapor to such an extent as to contain about 21% of its own weight of water when in equilibrium with water vapor at substantially 75 30° C. and a partial pressure of substantially 22 mm. of mercury.

8. A method of refrigeration, consisting in evaporating a liquid, adsorbing the vapor in a porous adsorbent material substantially 80 in the absence of permanent gases, removing the material from the vapor, liberating the adsorbed vapor from the material, condensing the vapor thus liberated and returning it to said liquid, cooling said material, and again bringing the material into contact with the vapor, said material being a hard porous gel having pores of such size that it will adsorb water vapor to such an extent as to contain about 21% of its own weight of water when in equilibrium with water vapor at substantially 85 30° C. and a partial pressure of substantially 22 mm. of mercury.

9. Apparatus of the character described, including in combination, an evaporator substantially free of permanent gases adapted to contain a body of liquid, an adsorber substantially free of permanent gases in communication with said evaporator, means to feed a porous adsorbing material through said adsorber but out of contact with said body of liquid, whereby the material adsorbs vapor from said liquid in its pores, an activator into which the material is discharged from the adsorber, means for sealing the adsorber and activator against the passage of vapor from one to the other, and means to return the activated material to the adsorber for another cycle.

10. Apparatus of the character described, including in combination, an adsorber having a part adapted to contain a body of liquid, means to maintain said adsorber substantially free of permanent gases, means to feed a porous adsorbent material through said adsorber but out of contact with said liquid, whereby the vapor from said liquid is adsorbed by said material, an activator into which said material is discharged from the adsorber, means for sealing said adsorber and activator against passage of vapor or gas from one to the other, and means to return the activated material from the activator to the adsorber for another cycle.

11. Apparatus of the character described, including in combination, an adsorber substantially free of permanent gases adapted in one part to contain a body of liquid, means to feed a porous adsorbent material through said adsorber but out of contact with said liquid, whereby the material adsorbs vapor from said liquid, an activator into which the material is discharged from the adsorber, means for sealing said adsorber and activator against passage of vapor or gas from one to the other, a condenser in communication with said activator and adsorber to condense and return to said body of liquid vapor driven off from the material in the activator, and means to return the activated material to the adsorber for another cycle. 70
12. Apparatus of the character described, including in combination, an adsorber substantially free of permanent gases, adapted in one part to contain a body of liquid, means to feed a porous adsorbing material through said adsorber but out of contact with said liquid, whereby the material adsorbs vapor from said liquid, an activator into which the material is discharged from the adsorber, means for sealing said adsorber and activator against passage of vapor or gas from one to the other, and means to cool and return the material from the activator to the adsorber for another cycle. 75
13. Apparatus of the character described, including in combination, a casing having two chambers, an evaporator adapted to contain a body of liquid, the first of said chambers being an adsorbing chamber and communicating with said evaporator, means to maintain said evaporator and adsorber substantially free of permanent gases, means to feed a porous adsorbent material through said adsorbing chamber and into the second chamber, means sealing said chambers against flow of vapor from one to the other, said second chamber constituting an activator and adapted to liberate the adsorbed vapor from the material, means to convey the activated material from the second chamber back through an opening into the first chamber, and means to prevent flow of vapor through the last mentioned opening. 80
14. Apparatus of the character described, including in combination, two chambers, an evaporator in communication with the first or adsorbing chamber, a liquid in said evaporator, means to feed a porous adsorbing material through said first chamber whereby vapor from the liquid is adsorbed by said material, a discharge conduit connecting said chambers, means to effect a flow of said material through said conduit, means to prevent flow of gas or vapor from one chamber to the other comprising means to maintain in said conduit a column of the material of sufficient length to resist movement because of the difference of pressures in the two chambers, said second chamber having therein means to activate the material, means to return vapor liberated from the material to said evaporator, and means to return the activated material from the second chamber to the first chamber. 85
15. Apparatus of the character described, including in combination, two chambers, an evaporator in communication with the first or adsorbing chamber, a liquid in said evaporator, means to feed a porous adsorbing material through the first chamber and discharge it into the second, whereby vapor from the liquid in the evaporator is adsorbed by the material, means in the second chamber for activating the material, a conduit connecting the second and first chambers, means for effecting a flow of the activated material in said conduit from the second to the first chamber, and means to seal said conduit against the flow of gas or vapor from one chamber to the other comprising means to maintain in the conduit a column of the material of sufficient length to resist movement because of difference of pressures in the two chambers. 90
16. Apparatus of the character described, including in combination, an evaporator adapted to contain liquid, an adsorber, an activator, means to feed a porous adsorbing material through said adsorber and discharge it into said activator wherein the material is liberated of the vapor adsorbed in the adsorber, means to return the material from the activator to the adsorber, and means to feed the material through the activator actuated from the means last above mentioned. 95
17. Apparatus of the character described, including in combination, an evaporator adapted to contain liquid, an adsorber adapted to contain a porous adsorbing material in communication with the evaporator, an activator adapted to liberate from the material vapor adsorbed in the adsorber, means within the adsorber to feed material therethrough and discharge it into the activator, a motor in said adsorber for actuating said means, and means to return the material from the activator to the adsorber actuated from the first mentioned means. 100
18. Apparatus of the character described, including in combination, an evaporator adapted to contain a supply of liquid, an adsorber in communication therewith, rotatable means to feed a porous material through said adsorber whereby vapor from the liquid is adsorbed in the pores of the material, an activator, means to feed the material therethrough, means to return the material from the activator to the adsorber, and a motor in the adsorber for actuating all of said means. 110
19. Apparatus of the character described, including in combination, an evaporator adapted to contain liquid, an adsorber in communication therewith, an activator, and 115

- means to circulate a porous adsorbent material through the adsorber and activator and back to the adsorber, whereby the material takes up vapor in its pores in the adsorber, has the vapor liberated in the activator and is then returned to the adsorber for use again. 5
20. Apparatus of the character described, including in combination, an evaporator adapted to contain liquid, an adsorber in communication therewith, an activator, means to circulate a porous adsorbent material through the adsorber and activator and back to the adsorber, whereby the material takes up vapor in its pores in the adsorber, has the vapor liberated in the activator and is then returned to the adsorber for use again, and a vacuum pump having its inlet connected to the adsorber for maintaining the adsorber and evaporator substantially free of permanent gases. 10
21. Apparatus of the character described, including in combination, an evaporator adapted to contain liquid, an adsorber in communication therewith, an activator, all of said parts being substantially free of permanent gases, means to circulate a porous adsorbent material through said adsorber and activator and back to the adsorber, whereby the material takes up vapor from the liquid in its pores in the adsorber and has the vapor liberated therefrom in the activator and is then returned to the adsorber for use again, and a condenser in communication with said activator and evaporator, whereby vapor liberated from the material in the activator is condensed and returned to the evaporator. 15
22. A method of refrigeration consisting in evaporating a liquid, adsorbing the vapor in a porous adsorbent material in the substantial absence of permanent gases, removing the material from the vapor, liberating the adsorbed vapor from the material, and again bringing the material into contact with the vapor. 20
23.
